HAT AND SWEATBAND THEREFOR.

Application filed May 26, 1928. Serial No. 280,881.

Our present invention relates to the manufacture of hats, and more particularly to an improved sweat band for hats and method of making the same.

5 A serious difficulty with regard to hats is the inability to prevent discoloration of the material of the hat by perspiration. In present day structures the ordinary sweat band is of absorbent material and perspiration 10 very soon wets such material through and excess of perspiration is taken up by the material of the hat itself and such hat material is rapidly discolored. While it has been suggested and occasionally attempted to 15 make sweat bands of impervious material, the resulting discomfort to the wearer of the hat because of the non-absorbing quality of the hat band has precluded its use.

In our present invention, we have obviated 20 the objections to prior structures and in carrying out our invention have devised an improved sweat band of impervious material and have associated therewith a sewing band of any material which enables the sweat 25 band proper to be properly attached to the hat structure and have associated with the impervious hat band a removable layer of absorbent material, which layer may be removed and renewed as occasion may require. 30 Further, the sweat band is so built as to form practically a reservoir to receive the excess of perspiration and the removable absorbent material is adapted to fit into such reservoir. We find it advantageous to perforate the 35 sweat band of impervious material, but in doing so retain the reservoir intact. The removable absorbent material may be placed in position in lightly felted condition and such will soon project through the perforations in the sweat band of impervious material 40 so as to have a plurality of points or projections in engagement with the head of the wearer. Instead of placing the removable absorbent material in position in a 45 lightly felted condition, the absorbent material may be manufactured with protuberances or projections on one face thereof adapted to register with the perforations in the sweat band.

50 The principal object of our invention, therefore, is an improved sweat band construction for hats and the like.

Another object of our invention is an improved method of forming sweat bands.

55 In the accompanying drawings, illustrat-

ing the preferred embodiment of our invention,

Fig. 1 is a perspective view of our improved sweat band construction partly broken away to show the method of assembling the same;

Fig. 2 is a sectional elevation through a portion of a hat and sweat band showing the method of attaching the sweat band to the hat; and

Fig. 3 is a detail of a manufactured form of absorbent material.

Referring to the drawings, 10 designates a sweat band of impervious material and of a length to encircle the inner circumference 70 of a crown 11 of a hat, such hat being provided also with the usual brim 12. The material forming the sweat band 10 is folded upon itself, as indicated by the numeral 13, such folded portion 13 lying parallel to but 75 spaced apart from the portion 10. It is obvious, therefore, that the space between the portion 10 and the folded portion 13 constitutes a reservoir which will hold perspiration or other liquid. On the face of the 80 portion 13 adjacent the crown 11 of the hat is attached a strip 14 which may be of any suitable material such as leather, fabric, or impervious stock such as the band 10, and such strip 14 has its lower edge 15 extending 85 to any desired distance below the lower edge of the meeting point of the elements 10 and 13. The extending portion 15 constitutes a sewing edge and by means of which the sweat band structure may be attached to the 90 meeting point of the crown 11 and brim 12, as indicated by the numeral 16. Near the parallelly arranged portions 10 and 13 and fitting into and filling the reservoir formed by the spacing of such elements 10 and 13 95 is a strip of absorbent material 17 which may be of felt, blotting paper, or other suitable material. Above the junction point of the elements 10 and 13 and as shown in Figs. 1 and 2, the impervious hat band element 10 is 100 provided with a plurality of perforations, which perforations may be arranged in any suitable design and if the absorbent material 17 is placed in position in lightly felted condition, the pressure thereon will force some 105 of the felted material through the perforations 18 and form thereby a plurality of protuberances or projections 19, which will extend outwardly and be flush with the engaging surface of the element 10.

Referring to Fig 3, there is shown a portion of a strip of absorbent material 20 similar in construction to the strip 17 but manufactured with a plurality of projections or protuberances 21 thereon, which protuberances are arranged in a design similar to the design of the perforations 18 in the sweat band element 10.

It is obvious that in a sweat band manufactured as above described that the fact that the element 10 may be of impervious material is not objectionable because of the fact that such material is provided with a plurality of perforations 18 through which 15 may extend projections 19 of a strip of absorbent material 17 and that perspiration cannot come in contact with the material of the crown 11 or brim 12 and an excess of perspiration will collect in the reservoir 20 formed by the two elements 10 and 13, both of which are of impervious material. Further, the reservoir formed by such elements 10 and 13 is not disturbed in any way when the sweat band is attached to the hat structure 25 because of the fact that the element 14

is secured to the element 13 and the sewing of the sweat band takes place through the attachment of the lower extending portion 15 of the element 14 to the hat structure.

Having thus described our invention, 20 which we claim as new is:

An improved sweat band for hats and the like comprising a sweat band element adapted to come into engagement with the head of the wearer, an element formed integral therewith and arranged to lie parallel to and spaced apart from each other, a sewing element attached to said second element and providing means for attaching the sweat band to a hat or other like structure, an 35 absorbent element lying between the first and second elements, said first element being provided with a plurality of perforations 40 therein, said absorbent element being provided with projections extending into said 45 perforations.

In testimony whereof, we have signed our names to this specification.

A. WALDO ROCKWOOD.
